DESIGN FOR A STRAP LEWIS FOR BURIAL VAULT PARTS

Wilbert W. Haase, Forest Park, Ill., assignor to
Wilbert W. Haase Co., Forest Park, Ill., a cor-
poration of Illinois

Application April 9, 1943, Serial No. 109,942

Term of patent 14 years

To all whom it may concern:

Be it known that I, Wilbert W. Haase, a citizen
of the United States of America, residing at For-
est Park, in the county of Cook and State of
Illinois, have invented a new, original, and ornamental
Design for a Strap Lewis for Burial Vault
Parts, of which the following is a specification,
reference being had to the accompanying draw-
ing, forming a part thereof.

Referring to the drawing;

Figure 1 is a perspective view of a strap lewis
for burial vault parts embodying my new design,
and,

Fig. 2 is an elevational view of the same.

I claim:

The ornamental design for a strap lewis for
burial vault parts, as shown.

WILBERT W. HAASE.
